SELF-LUBRICATING POLISH ROD

Robert N. Simon, Iraan, Tex.

Application September 1, 1954, Serial No. 453,608

2 Claims. (Cl. 255—28)

This invention relates to well-drilling equipment, and in particular, a self-lubricating polish rod having a threaded stud extended from one end of the rod and threaded into a well-drilling rod or string, such as a sucker rod, the polish rod being provided with a hollow shell that slips over one end of the core or body and that is clamped against the end of a mandrel at one end of the polish rod with a jam nut, and wherein shallow grooves and recesses in the surface of the shell feed lubricant to rubber packing rings of a stuffing box in which the polish rod is reciprocated whereby substantially all wear of the polish rod is taken by the shell and in which the shell is readily removable and replaceable so that the mandrel and body of the polish rod are adapted to be used indefinitely.

The purpose of this invention is to improve the construction of lubricating polish rods used in pumping wells whereby washers of the packing glands around the rods are lubricated continuously and wherein wear developing in a rod is taken by a removable shell on the rod.

With conventional polish rods that reciprocate through packing glands and the like, it is difficult to maintain lubrication on the parts with the result that the continuous rubbing action of the washers of packing glands wears polish rods of this type and as wear develops it is necessary to remove and replace the entire polish rod. With this thought in mind, this invention contemplates a comparatively thin shell clamped by a jam nut on the body of the polish rod whereby wear resulting from the rubbing action of the washers of the packing glands wears only the shell and with the shell readily removable and replaceable on the polish rod the body of the polish rod is adapted to be used indefinitely.

The object of this invention is, therefore, to provide means whereby wearing portions of polish rods adapted to be connected to sucker rods of pumping equipment of wells may be removed and replaced so that polish rods may be renewed without removing and replacing the entire body of the rod.

Another object of the invention is to provide an improved polish rod for the connecting rod of a pumping well in which means is provided in the surface of a shell on the rod for carrying lubricant to washers of packing glands through which the polish rod operates.

Another important object of the invention is to provide a polish rod with a removable shell extended over wearing portions thereof in which the shell is adapted to be removed and replaced by the average mechanic.

A further object of the invention is to provide an improved polish rod for pumping wells in which the rod is provided with a removable shell and in which the rod is of a simple and economical construction.

With these and other objects and advantages in view, the invention embodies a polish rod having a threaded stud extended from a mandrel at one end with the stud adapted to be threaded into a sucker rod and in which a shell having annular grooves and recesses in the sur-

2

face is adapted to be clamped on a stem extended from the mandrel with a jam nut.

Other features and advantages of the invention will appear from the following description taken in connection with the drawing, wherein:

Figure 1 is an exploded view showing the improved polish rod with the shell, that takes the wear, removed from a mandrel and stem and with the jam nut adapted to be placed on the opposite end of the shell.

Figure 2 is a longitudinal section through the improved polish rod with the parts assembled.

Figure 3 is a cross section through the rod taken on line 3—3 of Figure 2.

Figure 4 is a similar cross section extended through the rod and taken on line 4—4 of Figure 2.

Figure 5 is an end elevational view showing the body, mandrel and stem of the polish rod with the shell and jam nut removed and looking toward the threaded end of the stem.

Figure 6 is a detail showing an end elevational view of the removable and replaceable shell of the improved polish rod.

Referring now to the drawing, wherein like reference characters denote corresponding parts, the improved self-lubricating polish rod of this invention includes a shell 10 adapted to be positioned on a stem 11 extended from a mandrel 12, a jam nut 13 threaded on the stem, a threaded stud 14 extended from the mandrel, and a similar threaded stud 15 on the extended end of the jam nut 13.

As shown in the drawing, the body of the polish rod includes the mandrel 12, stem 11 and stud 14 and, as shown in Figure 2, the extended end of the stem 13 is provided with threads 16 on which the jam nut 13 is threaded. The end of the mandrel 12 from which the stem 11 extends is provided with an inwardly extended beveled surface 17 providing an annular groove 18 into which a beveled end 19 of the shell 10 extends, and with the end of the shell extended into the annular recess or groove, the part 19 of the shell is locked in position in the groove 18 with the jam nut 13. A split-spring lock washer 20 is positioned between the jam nut and the upper end of the shell 10 and, as shown in Figure 1, the outer or peripheral surface of a flange 21 extended around the jam nut is provided with flat surfaces 22 to facilitate rotating the jam nut with a wrench or the like. A similar nut or flange, as indicated by the numeral 23, is provided between the mandrel 12 and stud 14, the periphery of the flange being provided with flat surfaces 24 to facilitate gripping and turning the body of the polish rod with a wrench or the like.

The intermediate part of the shell 10 is provided with spaced annular grooves 25 and 26 and small recesses or pits 27, positioned between the grooves, which coat with the grooves to carry lubricant from the well string or casing in which the sucker rod is operating through the packing gland (not shown) in which the polish rod reciprocates whereby washers of the packing gland are lubricated as the device operates. With this means of supplying lubricant to the heavy leather washers that wear the surface of the polish rod, the wear on the shell 10 will be reduced to a minimum.

With the parts designed and assembled as shown and described, the polish rod is connected to the upper end of the conventional sucker rod of a pumping well with the stud 14 extended from the end of the mandrel 12 threaded in the sucker rod and with the stud 15 extended from the jam nut 13 threaded in an upwardly extended extension whereby the pumping rod is adapted to be reciprocated with the polish rod incorporated therein. The polish rod, moving upwardly and downwardly in the

stuffing box or packing gland, wears rapidly and it is necessary, in conventional equipment, to replace the polish rod periodically. With the improved structure of this invention, it is only necessary to remove the jam nut 13, slide the shell 10 from the stem 11 and replace the shell with a new shell, replacing the jam nut on the end of the stem 11. The cost of replacing the shell 10 is comparatively negligible as compared with the cost of replacing the entire polish rod assembly.

It will be understood that modifications, within the scope of the appended claims, may be made in the design and arrangement of the parts without departing from the spirit of the invention.

What is claimed is:

1. A polish rod for use in a pumping well comprising a mandrel having a flange with flat surfaces on the peripheral edge thereof on one end thereof, a stem having a threaded extended end extended from the opposite end thereof and a threaded stud extended from the flange, said mandrel having a conical groove in the end from which the stem extends circumjacent with said stem, a cylindrical shell having a frusto-conical shaped end positioned on the stem, a split-spring washer also mounted on the stem and positioned at the end of the shell, and a jam nut having a threaded stud extended therefrom threaded on the threaded end of the stem and adapted to urge the frusto-conical shaped end of the shell into the conical groove in the end of the mandrel. 15 20 25

2. A polish rod for use in a pumping well comprising a mandrel having a flange with flat surfaces on the peripheral edge thereof on one end thereof, a stem having a threaded extended end extended from the opposite end thereof and a threaded stud extended from the flange, said mandrel having a conical groove in the end from which the stem extends, a cylindrical shell having a frusto-conical shaped end positioned on the stem, a split-spring washer mounted on the opposite end of the stem and positioned at the end of the shell, and a jam nut having a threaded stud extended therefrom threaded on the threaded end of the stem and adapted to urge the frusto-conical shaped end of the shell into the conical groove in the end of the mandrel, said shell having spaced annular grooves and also recesses in the outer peripheral surface.
